UNITED STATES PATENT OFFICE.

HENRY F. CLEEVE, OF LYNDHURST, NEW JERSEY, AND JOHN PARKER, OF NEW YORK, N. Y., ASSIGNORS TO PHILIP HATHAWAY, OF NEW YORK, N. Y.

SODA-WATER APPARATUS.

SPECIFICATION forming part of Letters Patent No. 394,834, dated December 18, 1888.

Application filed March 17, 1888. Serial No. 267,481. (No model.)

To all whom it may concern:

Be it known that we, HENRY F. CLEEVE, a subject of the Queen of Great Britain, residing at Lyndhurst, in the county of Bergen and 5 State of New Jersey, and JOHN PARKER, a subject of the Queen of Great Britain, residing in the city and county of New York, in the State of New York, have invented a certain new and useful Improvement in Soda-Water Apparatus, of which the following is a specification.

We use the term "soda-water" in its popular sense to designate water which has been caused to absorb carbonic-acid gas, in which 15 it is retained under pressure.

The invention relates to the apparatus for manufacturing of the class known as "continuous," in which class the carbonic acid is manufactured at ordinary pressures and is 20 compressed by a pump.

Our improvements overcome the difficulties heretofore experienced from the heating of the pump when the water is shut off, avoiding the necessity of the ordinary water-jacket 25 around the pump, and works successfully and economically under all conditions without requiring attention. Whenever the pressure in the pump is in excess, gas or water, or both, are delivered back into the feed-box, and 30 whenever more gas is received in the feed-box than can be absorbed by the water at the moderate pressure which obtains there the excess will be delivered into the gasometer. The water also which escapes from the foun- 35 tain through the safety-valve when the water rises too high is also delivered into the feed-box, and as its excess of carbonic-acid gas escapes it is largely retained by the feed-water. The partial charging of the water with car- 40 bonic acid by this means previous to its introduction into the pump contributes to the rapidity and the economy of the process of charging.

The accompanying drawings form a part of 45 this specification and represent what we consider the best means of carrying out the invention.

Figure 1 is a vertical section, partly in elevation, showing the entire apparatus, and 50 Fig. 2 is a vertical section showing a portion on a larger scale.

Similar letters of reference indicate corresponding parts in both the figures where they occur.

A is the ordinary frame-work, and B the 55 pump, operated as usual, and delivering into the fountain C. It receives gas from the ordinary gasometer, D, through a pipe, d, and receives water from the feed-box E through a pipe, e. The capacities of these pipes d 60 and e may be controlled by stop-cocks, one stop-cock for each pipe, arranged and operated in the ordinary manner. Water is supplied to the feed-box through a pipe, f, controlled by a stop-cock, f', operated by a float. 65

So far as yet described the apparatus is constructed and operated in the long-approved manner. The provisions for introducing a constant or intermittent supply of carbonic-acid gas at ordinary pressures into 70 the gasometer D and for taking the water from the fountain C and bottling or otherwise utilizing it may be of any ordinary or suitable character and need not be represented.

A safety-valve, G, is mounted on the fountain C, and when through a temporary cessation of the bottling or other cause, the continued working of the pump B accumulates too much pressure in the fountain the safety-valve opens and relieves the pressure; but 75 instead of, as usual, connecting to the top of the fountain, this safety-valve is provided with a pipe, g*, reaching down in the interior of the fountain. Its lower open end is at the level to which it is desired to limit the rise of 80 the water. So long as the water-level is below this point gas alone will be delivered through the safety-valve; but when the water-level rises above this point water alone 85 will be delivered. Under ordinary conditions 90 the pressure, when in excess, will find the water-level so close to the lower end of this tube that the saturated water and gas will be delivered together in varying proportions through the safety-valve. A flexible dia- 95 phragm, H, connects the stem of the safety-valve with an inclosing-casing, G', as fully shown in Fig. 2. The upper portion of the casing allows the stem to move loosely and freely up and down with no attempt at tight- 100 ness. It is simply guided. But the diaphragm H below forms an impermeable barrier for

the gas, which is thus restrained and compelled to flow away through the pipe *g*, which extends into and along the bottom of the interior of the feed-box *E*, where it is provided 5 with fine perforations *g'*.

The mingled gas and water, or either alone, rising through the safety-valve *G*, is disposed of as follows: The water thus rising flows through the pipe *g* and the apertures *g'* to 10 mingle with the fresh water in the feed-box. The gas thus rising through the safety-valve *G*, as also the gas given off from the saturated water on its release from pressure, is restrained by the diaphragm *H* and caused to 15 flow through the same pipe *g*. It is distributed in the feed-box *E* through the apertures *g'*. On rising in fine bubbles it is absorbed by the water until the latter is partially saturated. Any excess of gas not thus absorbed 20 will pass through a second safety-valve, *K*, which may be lightly loaded, and is delivered through *k* into the gasometer *D*.

There are frequently-recurring intervals in the continuous process of charging water with 25 gas in which an excess of pressure exists in the fountain and is relieved by the safety-valve *G*. Our apparatus insures that water shall be delivered instead of gas if the water tends to rise too high, and insures that 30 whether water or gas it shall all be retained and delivered into the feed-box without materially affecting the delicacy of the safety-valve. It contributes to the economy of the process and to the efficiency of the apparatus 35 of given capacity by causing the water to be delivered from the feed-box already partially saturated with the gas. An excess is promptly delivered into the gasometer and occasions no difficulty.

40 It is important to keep a liberal quantity of the gas under pressure in the fountain as a means of maintaining the pressure and the saturated condition of the water when the water-level in the fountain is lowered by rapid 45 bottling. The importance of this has been so fully recognized that expensive apparatus has been heretofore employed, operating by the weight of the fountain to check the water-supply and increase the proportion of gas when 50 ever the water-level tended to rise too high. Our causing the safety-valve *G* to communicate with the interior of the fountain at a low point attains practically the same end.

When the water is shut off and the pump 55 *B* treats gas alone, it becomes heated to such an extent as to ruin leather packings. A jacket around the pump, through which a constant stream of cold water is caused to flow, reduces the risk from this source. Our appa- 60 ratus avoids the necessity for such cumbersome and imperfect devices. Our pump may be allowed to pump a constant supply of water,

the excess being delivered back into the feed-box without loss, thus insuring a proper condition of the pump and packing. 65

Modifications may be made without departing from the principle or sacrificing the advantages of the invention. When the fresh water is received through the pipe *f* at a sufficient pressure, the second safety-valve, *K*, 70 may be loaded so as to maintain a considerable pressure in the feed-box, which will allow a still greater degree of saturation of the water therein. It will be understood that in such case the load on the safety-valve *G* 75 should be proportionately lessened, so it will rise against the pressure above it and properly relieve the fountain, avoiding the possibility of an excess therein.

We have described the invention with particular reference to the manufacture of soda-water; but it will be understood that the apparatus may be used successfully in charging other liquids, as cider, wine, &c. 80

We claim as our invention— 85

1. In an apparatus for soda-water manufacture, the fountain *C*, gas-pipe *d*, connecting with the gasometer *D*, feed-box *E*, water-pipe *e*, and provisions, as the pump *B*, for introducing water and gas into the fountain, in 90 combination with each other and with the safety-valve *G* and pipe *g*, leading gas and water from the fountain back to the feed-box, all substantially as herein specified.

2. In an apparatus for soda-water manufacture, the safety-valve *G* and connection *g*, leading therefrom to the feed-box *E*, in combination with the fountain *C*, feed-box *E*, and gasometer *D*, and with the connection *k*, leading from the feed-box to the gasometer, so 100 that the gas and water escaping from the fountain is delivered into the feed-box and the gas not absorbed by the water in the feed-box is discharged into the gasometer, as herein specified. 105

3. In a soda-water apparatus, the safety-valve *G* on the fountain *C*, having a connection, *g'*, communicating with the interior of the fountain at the desired water-level in the latter, so as in delivering to relieve the gases 110 of pressure it will deliver water whenever the water rises above that level and gas when it is below that level, substantially as and for the purposes herein specified.

In testimony whereof we have herenunto set 115 our hands, at New York city, this 16th day of March, 1888, in the presence of two subscribing witnesses.

HENRY F. CLEEVE.
JOHN PARKER.
